SLAT FOR VENETIAN BLINDS

Melvin W. Howard, Toledo, Ohio, assignor to
Solon O. Richardson, III, Perrysburg, Ohio

Application March 14, 1935, Serial No. 11,096

1 Claim. (Cl. 156—17)

This invention relates to Venetian blinds, and is more particularly directed to the slat portion of such blinds.

The primary object of the invention is the provision of an inexpensive, easily replaceable slat for a Venetian blind which may be formed of paper board or other fibrous substance and which, when in use, imparts novel and decorative effects to the blind.

Another object of the invention is the provision of a slat for a Venetian blind which permits a maximum ventilating opening and at the same time decreases the direct transmission of light through the blind.

Another object of the invention is the provision of a slat of this character which is adapted to nest closely against adjacent slats when the blind is in closed position to more completely prevent the transmission of light.

Other objects and advantages of the invention will become apparent as the description proceeds, reference being had to the accompanying drawing in which—

Figure 1 is an elevation of a blind having slats formed in accordance with the present invention; Fig. 2 is a section on line 2—2 of Fig. 1; Fig. 3 is an enlarged fragmentary sectional view of the slats in another position; Fig. 4 is a view with the slats in closed position, and Fig. 5 is a fragmentary perspective view of a slat formed in accordance with the present invention.

Referring to the drawing, the present invention is shown in connection with a window having a frame 1 defining the window opening. The window sash and glass are omitted in the interests of clarity since the present invention is not concerned with these parts. On the inside of the window frame suitable hanging fixtures 3 are provided to support the blind and retain it in any desired position. A header strip 5 is pivotally mounted at its ends on pins 7 to each of the hanging fixtures and is adapted to be controlled in its position by a cord 9 adjacent one end which is looped about the header strip and trained through a suitable pulley 11 conveniently fixed to the top of the window frame 1.

The blind itself comprises spaced inner and outer tapes 13 and 14. The tapes are preferably fixed to the header strip 5 and depend therefrom to points adjacent the bottom of the window opening where they receive a bottom strip 15. Obviously, the number of tapes used in making up a blind will depend entirely on the width of the window opening, as the tapes must be so spaced

as to afford the proper support for the slats in a manner hereinafter described.

A plurality of slat supporting webs 17 are provided at intervals to span the distance between the inner and outer tapes of a pair and are preferably woven into the material from which the tapes are made.

The present invention is particularly concerned with the slats to be used in the blind. As shown in Fig. 5, the slat is composed of a body portion 19 having an integral downturned supporting flange 20 at one edge, disposed in a plane substantially normal to the plane of the body portion 19. The slat is preferably made of paper board or other inexpensive material and can obviously be decorated in any desired color or pattern. Inasmuch as paper board is preferably used in this slat, the supporting flange 20 must be disposed at an angle with relation to the body of the slat sufficiently great to prevent sagging of the slat when in use, and to support the body portion in an even horizontal plane. In use the slats are inserted between the inner and outer tapes 13 and 14 and are allowed to rest loosely on the webs 17 so that they are superposed in a manner similar to the conventional Venetian blind. The downturned supporting flanges 20 are faced outwardly of the window opening and act as miniature, individual awnings for the area between the body portion of each pair of slats. When the slats are rotated to a position such that the body portion is lower on the outside of the blind than on the inside, this effect is particularly noticeable since the downturned flange 20 is then in a position to interrupt the direct rays of the sun. At the same time the blind is not turned to such an extent that the ventilation is materially decreased by reason of an appreciable restriction of the available air passage between the slats. It is also found in use that the flanges 20 direct the light rays in such a manner as to cause a shading of the light on the underside of each slat and thus produce novel and distinctive lighting effects.

The slat shaped in accordance with the present invention also lends itself to a complete closure of the window opening as is apparent in Fig. 4. As there shown, the header strip 5 is turned so that the upper outer edge of each slat is substantially in contact with the lower inner edge of the slat disposed immediately above it. It will be seen that the degree of rotation necessary to be imparted to the header strip 5 to accomplish this complete closing is considerably less than 45°.

with straight slats due to the offset produced by the downward flanges 20. Inasmuch as the header strip 5 is turned by the conventional pulley and cord 9, this feature becomes important since the 5 cord 9 is not well adapted to a complete turning of the header strip, and the limit of its motion is approximately that shown in Fig. 4.

Obviously, the slats may be easily replaced since they are disposed loosely on the webs 17. Since 10 they are preferably made of paper board, fibrous, plastic or similar inexpensive material, the cost involved in changing the entire decorative effect of the window opening is relatively slight.

15 While the invention has been described in connection with a particular type of operating mech-

anism, it will be appreciated that numerous changes may be made in the form and disposition of the parts without departing from the invention as defined in the appended claim.

What I claim is:

In a Venetian blind having vertically spaced slat supporting webs, a slat comprising a body having an integral downturned supporting flange at one end disposed in a plane substantially normal to the plane of the major part of said body, 10 said slat being supported by the edge of said flange and by the opposite edge of said body, whereby the flange imparts stiffness to the slat to prevent sagging thereof.
